UNITED STATES PATENT OFFICE.

PATRICK H. QUINN, OF SOMERVILLE, MASSACHUSETTS.

BOTTLE-CAP.

1,128,509.

Specification of Letters Patent.

Patented Feb. 16, 1915.

Application filed April 27, 1914. Serial No. 834,781.

To all whom it may concern:

Be it known that I, PATRICK H. QUINN, a citizen of the United States, residing at Somerville, in the county of Middlesex and State of Massachusetts, have invented certain new and useful Improvements in Bottle-Caps, of which the following is a specification, reference being had to the accompanying drawings.

10 This invention relates to bottle caps or analogous devices, and particularly to an extracting means therefor; and it has for its primary object the provision of extracting means that can be advantageously applied to the ordinary paper disk commonly used as a closure for milk bottles, and it is intended that the said means be formed from a single length of tape of suitable texture which may be looped through the central 15 portion of the disk and terminally secured to the under side of the disk and provided above the disk and at the center thereof with a relatively flexible manipulating loop which may be freely grasped between the fingers 20 of the hand of the operator when it is desired to remove the cap from the bottle.

Another object of the invention is the provision of an extracting device which may be used in connection with paper disks and 25 connected therewith so as to prevent the disk from leaking at its point of connection with the device.

A further object of the invention is the provision of a device of this character which 30 will consist of a disk having a central vertical slit and an extracting element formed of a single length of tape having a width exceeding the length of the slit, so that the tape will be snugly confined in the slit and 35 thereby cause the slit to be positively sealed.

With these and other objects in view, the invention consists of certain novel features of construction, combination and arrangement of parts, as will be hereinafter described and claimed.

In the accompanying drawings:—Figure 1 is a perspective view of a cap or disk, showing the application of the extracting device thereto; Fig. 2 is a vertical section 40 therethrough; Fig. 3 is a plan view of the disk, showing the extracting device re-

moved; and Fig. 4 is a plan view of the tape.

The disk 1, aside from the centrally located slit 2 is of a form commonly used upon milk bottles, so as to serve as a closure therefor. The slit extends entirely through the disk, and, as shown, the loop 3 of an extracting tape 4 is passed through the slit.

The tape has a width exceeding the length 60 of the slit 2, so that portions of the tape will be snugly confined between the walls of the slit, and, as a consequence of this arrangement, the slit will be sealed and the contents of the bottle will be held against 65 leaking from the slit. The tape is formed of a single length of textile material having a body of sufficient texture to permit of the application of necessary pull thereto without causing a separation of the extracting 70 loop of the tape from the attaching portion thereof. The terminals 5, 5 of the tape are respectively extended in opposite directions beneath the disk and the said terminals are treated to a water-proof cement 6, which is 75 secured to the under side of the disk, whereby the main attaching part of the tape thus becomes impervious and additional sealing of the slit 2 is satisfactorily effected and leakage of the disk at this point is properly 80 eliminated.

While the device is particularly designed to be used in connection with milk bottle caps it is obviously to be understood that I do not propose to limit myself to the application of the device as it may be used on various forms of receptacles having removable closures that are adapted to be lifted from the open end of the receptacle. It is also to be understood that by making the 85 extracting tape in the manner specified that the same may be readily adjusted against the upper surface of the cap to lie in a flat condition thereon, so that the cap may be 90 operatively fed from any well known form of capping machine without the loop 3 interfering with the discharge of the cap from the machine.

I claim:—

As a new article of manufacture, a sealing cap having a radially disposed elongated slit intersecting its axial center, and

an extracting tape of textile material folded on itself intermediate its length and having its free extremities projected through the slit, the projected portions of the extremities being directly secured to the under face of the cap, said tape being of a width in excess of the length of the slit.

In testimony whereof I hereunto affix my signature in the presence of two witnesses.

PATRICK H. QUINN.
